CLAIM

I claim the ornamental design for a razor cartridge guard, as shown and described.

DESCRIPTION

FIG. 1 is a front perspective of a razor cartridge, according to an embodiment of my new design;

FIG. 2 is a bottom perspective of a razor cartridge, according to an embodiment of my new design;

FIG. 3 is a front elevational view of a razor cartridge, according to an embodiment of my new design;

FIG. 4 is a rear elevational view of a razor cartridge, according to an embodiment of my new design;

FIG. 5 is a top plan view of a razor cartridge, according to an embodiment of my new design;

FIG. 6 is a bottom plan view of a razor cartridge, according to an embodiment of my new design;

FIG. 7 is a left elevational view of a razor cartridge, according to an embodiment of my new design; and,

FIG. 8 is a right elevational view of a razor cartridge, according to an embodiment of my new design.

The broken lines illustrate the environment of the razor cartridge guard and form no part of the claimed design.
